UNITED STATES PATENT OFFICE.

ROBERT R. HUGHES, JR., OF NEW YORK, N. Y., ASSIGNOR TO UNION SPECIAL MACHINE COMPANY, OF CHICAGO, ILLINOIS, A CORPORATION OF ILLINOIS.

PRESSER-FOOT FOR SEWING-MACHINES.

1,275,694.

Specification of Letters Patent. Patented Aug. 13, 1918.

Application filed September 19, 1914. Serial No. 862,537.

To all whom it may concern:

Be it known that I, ROBERT R. HUGHES, Jr., a citizen of the United States, residing at New York, in the county of New York, State of New York, have invented certain new and useful Improvements in Presser-Foots for Sewing-Machines, of which the following is a description, reference being had to the accompanying drawing and to the figures of reference marked thereon.

The invention relates to new and useful improvements in a presser foot for sewing machines, and more particularly to a presser foot which is adapted to guide a strip which is to be stitched to a fabric.

It is often desirable to fold the edges of a bias strip and to stitch the same to a garment. These strips are stitched at each edge and often have very sharp curves, especially when applied to belts, cuffs and collars, and the like. An object of the present invention is to provide a presser foot which will guide and hold a bias strip with its edges folded as it is being stitched and while turning curves so that a line of stitching may be inserted in proper relation to each folded edge.

A further object of the invention is to provide a presser foot of the above character with means for turning in and folding the edges of the bias strip.

These and other objects will in part be obvious and will in part be hereinafter more fully disclosed.

In the drawings which show by way of illustration one embodiment of the invention:

Figure 1 is a side view of a presser foot embodying my invention, also showing feed dog, throat plate and needles.

Fig. 2 is a view in vertical section therethrough,

Fig. 3 is a plan view of the presser foot showing a bias strip stitched to a body fabric.

Fig. 4 is a bottom plan view of the presser foot.

Fig. 5 is a sectional view on the line 5—5 of Fig. 2.

Fig. 6 is a sectional view on the line 6—6 of Fig. 3.

Fig. 7 is a view showing a bias strip with its edges folded and stitched to a body fabric.

Fig. 8 is a plan view of throat plate and feed dog.

The invention consists generally in providing a presser foot with means for guiding and folding the edges of a bias strip and directing said strip with its edges folded underneath the main portion of the presser foot. The presser foot is provided on its lower face with a guiding groove which is substantially the width of the folded strip, and a yielding spring member presses against the strip on the under surface thereof and holds the same seated in the guiding groove until the strip is stitched. The foot is also provided with needle openings, one of which is preferably arranged in advance of the other as this presser foot is especially adapted for use with a two needle machine, wherein the needles are set in a line oblique to the line of feed. These needle openings pass through the foot at points adjacent the edges of the groove in the under face thereof.

The yielding member is cut away to permit the free passage of the needles but extends to a point in rear of both needles.

Referring more in detail to the drawings, my improved presser foot consists of a shank 1 which is adapted to be attached to a presser bar 2, and said shank carries a main foot portion 3. Extending upwardly from the front end of the foot portion there is an extension 4. This extension 4 receives the strip S which is to be folded and stitched to the body fabric indicated at F in Figs. 2 and 7. This extension 4 is bent so as to form a guiding and folding space 5 for this strip S. The edges of the guiding extension are separated as at 6. Extending through the extension 4 is a folding tongue 7 which is provided with a strengthening rib 8. The fabric strip, as shown in Fig. 5, is folded so that the edges of the strip are carried around underneath the body portion of the strip. This strip is preferably made of a bias fabric so that the strip may be readily applied to sharp curves in the garment to which it is to be attached. The presser foot carrying the extension 4 has a rearwardly extending groove 9 in its under face, see Figs. 4 and 6. This groove is substantially the same width as the folded bias strip and

is sufficiently deep to completely house the strip so that the vertical edges of the groove become guiding edges for the folded strip. Said foot has two needle openings 10 and 11. These needle openings are so disposed as to pass through the foot adjacent the side edges of and within the groove 9. The two needle openings 10 and 11 are set in a line diagonal to the line of feed and the foot is especially adapted to be used in connection with a chain stitch sewing machine wherein two independent lines of stitches are produced. The groove 9 terminates directly in rear of the rearmost needle opening 11. The extension 4 is provided with the supporting block 12 to which is attached a yielding plate 13 by means of a suitable screw 14. This plate 13 extends underneath the presser foot and terminates substantially at the end of the groove 9. The yielding plate 13 is of substantially the same width as the groove 9 although there is enough clearance to permit this plate to yield freely in the groove. The plate is cut away at 15 to permit the needle to freely pass through the opening 10 and is also cut away at 16 to permit the needle operating in the opening 11 to pass by said plate. The purpose of this yielding plate is to hold the folded strip well seated in the groove in the under face of the presser foot until the stitches are formed. Coöperating with this presser foot is a throat plate 17 having feed slots 18 therein, a central feed slot extends forward between the needle openings 19 and 20 formed in the throat plate, feed dog 21 has a forwardly projecting central portion 22 which works in this central slot and this engages the fabric F to which the strip is to be stitched. The needle 23 passes through the needle opening 11 in the presser foot while the needle 24 passes through the needle opening 10 therein. Coöperating with these needles beneath the work support is any suitable complementary stitch forming mechanism. The stitch forming mechanism is preferably of a type wherein two independent lines of stitching are formed.

Inasmuch as the groove in the presser foot terminates directly in rear of the needles, the presser foot is especially adapted for guiding a folded bias strip so that it may be stitched around sharp curves, as indicated at Fig. 3. A great deal of trouble has been experienced in stitching folded strips around sharp curves. Heretofore, the attaching of these strips has been done on a single needle machine requiring two operations. With my improved presser foot, however, the strip is laid perfectly flat and smooth and a line of stitching passed through the strip both at the inside and the outside edges thereof and even when stitching curves. This is accomplished by aid of the groove in the bottom

of the presser foot, together with the steel spring or yielding plate which holds the folded strip in said groove. This spring fits close to both needles and, therefore, holds the folded strip tightly in the groove of the foot until it is stitched and prevents it running off the inside of the curve or widening at the outside of the curve.

It is obvious that minor changes in the details of construction may be made without departing from the spirit of the invention as set forth in the appended claims.

Having thus described my invention, what I claim as new and desire to secure by Letters Patent is;

1. A presser foot for sewing machines comprising a foot portion having a groove in its under face and needle openings extending through the foot portion into said groove, said needle openings being located adjacent the side edges of the groove, and a yielding member carried by said foot and adapted to engage a folded strip in rear of each needle, whereby said folded strip is held in the groove until stitched.

2. A presser foot for sewing machines comprising a foot portion having a groove in its under face and needle openings extending through the foot portion into said groove, said needle openings being located adjacent the side edges of the groove, and a yielding member carried by said foot and adapted to engage a folded strip in rear of each needle, whereby said folded strip is held in the groove until stitched, said groove in the under face of said foot terminating at a point directly in rear of the needles whereby said folded strip may be stitched in a sharp curve.

3. A presser foot for sewing machines comprising a foot portion having a groove in its under face, needle openings arranged in a line diagonal to the line of feed and extending through the foot portion into said groove adjacent the respective side edges thereof, a yielding plate carried by the presser foot at the forward end thereof and extending underneath the same to a point in rear of each needle, said plate being narrower than the groove and engaging a folded strip lying in said groove.

4. A presser foot for sewing machines comprising a foot portion having a groove in its under face, needle openings arranged in a line diagonal to the line of feed and extending through the foot portion into said groove adjacent the respective side edges thereof, a yielding plate carried by said presser foot and extending underneath the same, said plate being narrower than the groove and engaging a folded strip lying in the groove, said groove terminating directly in rear of the rear needle, and said yielding plate being extended between the

needles and terminating substantially at the end of said groove.

5. A presser foot for sewing machines comprising a foot portion having a groove 5 in its under face and needle openings extending through the foot portion into said groove adjacent the respective side edges thereof, said presser foot having an extension provided with means for folding the 10 side edges of a strip and guiding the folded strip into said groove, said needle openings being arranged in a line diagonal to the line of feed and said groove terminating directly in rear of the rear needle opening, 15 a spring plate carried by the presser foot extension and extending underneath said foot, said plate being narrower than the groove and terminating at the rear end of the groove.
- 20 6. The combination with stitch forming mechanism, a presser foot and feed dog, of a folder for folding one edge of a strip onto the body thereof and a yielding member carried by one of said elements and 25 adapted to engage the folded edge of the strip both in front and in rear of the stitching point for retaining the folded strip in line with the feed until said strip is stitched.
7. In combination with a stitch forming 30 mechanism, including a pair of needles, a presser foot and a feed dog, of a folder for folding one edge of a strip on the body thereof, and a yieldable plate carried by

one of said elements and extending rearwardly between the needles for retaining 35 the folded strip in line with the line of feed, until said strip is stitched.

8. The combination with a presser foot having a rearwardly extending groove in its under face for receiving a folded strip 40 of fabric, of a folder for said strip extending forwardly from the front end of said foot and having its delivery end merging with the front end of said groove, and a yielding member carried by one of said elements 45 and extending substantially to the rear end of said groove for retaining the folded strip within the groove until stitched.

9. The combination with a presser foot having a rearwardly extending groove in 50 its under face for receiving a folded strip of fabric, of a folder for said strip extending forwardly from the front end of said foot and having its delivery end merging with the front end of said groove, and a 55 yieldable plate carried by said folder and having its free end passing the delivery end of the folder and terminating in the rear end of said groove for retaining the folded strip within the groove until stitched. 60

In testimony whereof, I affix my signature, in the presence of two witnesses.
